CHARACTER FRAME

Lawrence E. Baer, Attleboro, Mass., assignor to
The Baer & Wilde Company, a corporation of
Massachusetts

Application July 18, 1935, Serial No. 32,022

3 Claims. (Cl. 40—140)

This invention relates to a cravat holder; and has for one of its objects the provision of means for individual identification of the cravat holder, such as providing the initials of the name of the wearer of the cravat holder, the construction being such that these initials may be easily mounted by the retailer at the time of purchase of the cravat holder.

Another object of the invention is the provision of a frame-like structure for removably mounting different characters therein which will be suspended between the ends of a chain which encircles the tie, and which will serve by reason of its weight when hung as a pendant to retain the flexible chain in a certain desired position about the tie while the same is in use, while serving as an elongated link of the chain and enhancing the appearance of the device.

Another object of the invention is a very simple form of initial frame made of a single piece of stock and including sideways, retaining fingers and eyes for mounting it in pendant relation.

Another object of the invention is to provide means to positively space the characters predetermined distances apart that an equalized and symmetrical appearance may be had.

With these and other objects in view, the invention consists of certain novel features of construction, as will be more fully described, and particularly pointed out in the appended claims.

In the accompanying drawing:

Fig. 1 is a perspective view showing the device as mounted on a tie when in use;

Fig. 2 is a front elevation of the device as removed from the tie and shirt;

Fig. 3 is a perspective view of the blanked out form of stock for making the character frame;

Fig. 4 is a perspective view looking at the back of the frame, after the portions at the top and bottom edges thereof have been folded into the desired position;

Fig. 5 is a section on line 5—5 of Figure 4;

Fig. 6 is a section on line 6—6 of Figure 2;

Fig. 7 is a perspective view of two of the initials or characters in spaced relation;

Fig. 8 is a similar perspective view showing the character in contact and spaced by the fins at the top and bottom;

Fig. 9 is a front elevation of a key chain shown as comprising the character frame which I have shown in the above figures.

It is frequently desirable in jewelry manufacture to provide some sort of a device for enabling the article to be distinctive in one way or

another, or to particularly apply to a certain person, such for instance as having some sort of a character or characters such as the initials of his name provided on the article for this purpose; and in order to employ such distinction I have provided a frame-like structure capable of receiving initials which are removably mounted thereon in symmetrical relation and are held in position by bendable fingers, and I have so formed this frame structure that all of its parts are provided from a single piece of material, there being no soldering, riveting or other additional means necessary for the assembling of the frame, the same being merely shaped and bent into the required shape for the reception of the initials, characters or other inserts into the structure, the same being particularly adaptable for pending from a chain such as a cravat chain or other like relation; and the following is a more detailed description of the present embodiment of this invention, illustrating the preferred means by which these advantageous results may be accomplished:

With reference to the drawing, the character frame designated generally 10 is cut from a sheet 25 of stock in the shape shown in Figure 3 providing a front plate 11 with an obverse opening 12. At the upper corners of this plate the stock extends outwardly to provide ears 13 each having an opening 14 therein for the attachment of some sort of means for suspending the frame from a chain or other device, causing it to have a pendant-like effect.

Between the ears 13, the stock 15 is folded to provide a rearwardly extending flange 16 which 35 is then again folded downwardly providing a lip 17 spaced from the rear surface 18 of the plate 11 and forming a guideway 19 for sliding the edge of the character thereinto. The stock 20 along the lower edge of the frame or plate is 40 folded to provide a rearwardly extending flange 21 and then is bent upwardly providing a lip 22 spaced from the surface of the plate 18 and providing a channel 23 for the reception of the lower edge of a character 24 which may be slid into 45 the upper channel 19 and lower channel 23 along the back of the frame or plate.

Each character is provided with an upper and lower spacing fin 26 to fit beneath the lips on the frame, and this fin extends laterally on either side of the character so as to abut with a like fin on the next adjacent character and provide a definite spaced relation between adjacent characters that a symmetrical location of these char- 55

acters in the frame may be had. This relation is shown in Figure 7.

5 Fingers 25 are provided on the ends of the lip 22 which may be forced against the back of the plate to form obstruction, as shown in Figure 4, to block the removal of the characters 24 from the frame after being inserted therein.

10 In some cases, it will be desirable to attach to the connecting eyes 13 a flexible element such as a chain 27 to suspend the frame from the opposite ends of a clip 28 which may slide onto the shirt or be provided with any means for fastening to the shirt, thus providing the initial frame in a cravat holder.

15 The particular structure of cravat holder here shown consists of a front bar 29 of wire or the like and a rear jaw 30 formed of another piece of wire which may be fastened thereto. This front bar is provided with eyes 31 and a ring 32 20 or any suitable means for attachment of the flexible element.

25 In some cases instead of mounting the character frame on a cravat holder, as shown in Figure 2, I may mount the frame on a chain 33 as shown in Figure 9, in which case the pendant chains 34 and 35 are attached to ears 36 one at each end of the frame, while a horseshoe or some other suitable key stop 37 is provided at its opposite end. In this particular case, the frame serves to 30 obstruct removal of the keys which may be threaded onto the chain 33 over the horseshoe in a known way and will prevent the keys from coming off of the chain after positioned thereon.

35 The frame with the initials mounted therein, as shown in Figures 1 and 2, serves to space the ends of the flexible element 27 apart and in a definite relation and although it serves as a weight to hold the flexible elements in a certain definite relation, yet I prefer to form the chain 40 of such weight relative to the frame that when the device is displayed, such as is shown in Figure 2, the chain will bow out by reason of its weight which occurs by reason of the frame being relatively light in comparison to the wire 45 of the chain so that when displayed the curved relation is had rather than a severe straight relation which would be had if the weight of the frame were sufficiently heavy to pull the chain 27 taut.

The foregoing description is directed solely towards the construction illustrated, but I desire it to be understood that I reserve the privilege of resorting to all the mechanical changes to which the device is susceptible, the invention being defined and limited only by the terms of the appended claims. 5

I claim:

1. A character mounting for jewelry comprising a generally rectangular frame of sheet material, integral ears in the plane of the stock of the frame adjacent the upper corners thereof for suspending the frame, a guideway along the upper edge of the frame folded from the stock of the frame, and a guideway at the lower edge of the 15 frame folded from the sheet stock of the frame and provided with fingers located adjacent the lower corners of the frame in balanced relation with reference to said ears and providing with said ears a symmetrical disposition of the sheet 20 stock for both suspending the frame and locking the characters in position.

2. A character mounting for jewelry comprising a generally rectangular frame of sheet material, integral ears in the plane of the stock of the frame adjacent the upper corners thereof for suspending the frame, a guide way along the upper edge of the frame folded from the stock of the frame, and a guideway at the lower edge of the 25 frame folded from the sheet stock of the frame and provided with fingers located adjacent the lower corners of the frame, said ears and fingers being at least partially within the plane of the vertical edges of said frame and symmetrically disposed of said frame with reference 30 to each other.

3. A character mounting for jewelry comprising a generally rectangular frame of sheet material, integral ears at the upper portion thereof for suspending the frame, a guideway along the 40 upper edge of the frame folded from the stock of the frame, and a guideway at the lower edge of the frame folded from the sheet stock of the frame and fingers adjacent the end of the lower guideways in balanced relation with reference to 45 said ears and providing with said ears a symmetrical disposition of the sheet stock for both suspending the frame and locking the characters in position.

LAWRENCE E. BAER.
